UNITED STATES PATENT OFFICE

CHARLES LAWRENCE STOKES, OF LOS ANGELES, CALIFORNIA, ASSIGNOR TO CURTIS B. CAMP, TRUSTEE, OF GLENCOE, ILLINOIS

AUTOMATIC FUEL REGULATOR

Application filed December 30, 1926. Serial No. 157,979.

My invention relates to improvements in automatic fuel regulation for internal combustion engines.

The principal object of my invention is to provide a proper fuel and air mixture to an internal combustion engine, under varying temperature conditions, for starting and operating the engine.

Another object is to provide an automatic device for internal combustion engines, actuated by the suction thereof, for properly proportioning the mixtures of fuel and air supplied thereto.

Another object is to provide an automatic device for an internal combustion engine, actuated by the suction and temperature thereof, for properly proportioning the mixtures of fuel and air supplied thereto.

A further object is to provide a simplified carburetor for internal combustion engines, the functions thereof being automatically controlled by engine suction.

This application discloses in part the subject matter as my copending applications, Serial No. 676,864, filed Nov. 24, 1923, and Serial No. 715,912, filed May 26, 1924.

Referring to the drawings, in which the same numbers indicate like parts;

Fig. 1 is a side view showing the general application of my invention to an internal combustion engine;

Fig. 2 is a vertical longitudinal cross section of a carburetor;

Fig. 3 is a transverse cross section along the lines 3—3 of Fig. 2;

Fig. 4 is a rear view of part of Figs. 1 and 2, and a side view of part of Fig. 3;

Fig. 5 is a side view of a modification applied to an internal combustion engine;

Fig. 6 is a vertical longitudinal cross section of the modification shown in Fig. 5; and

Fig. 7 is a transverse cross section along the lines 7—7 of Fig. 6.

Referring to Figs. 1 to 4 inclusive; an internal combustion engine 1 has an exhaust pipe 2 and an intake manifold 3, to which latter is attached a carburetor 4 having a main air intake 5 and the usual float chamber 6 open to atmosphere and supplied in any well known manner with fuel through

a feed pipe 7, whereby a constant level of liquid fuel X—X is maintained therein.

Carburetor 4 includes a mixing chamber 8, the outlet from which is controlled by a butterfly throttle valve 9 and the anterior portion of chamber 8 is controlled by a choker valve 10 placed in passage 5.

Mixing chamber 8 contains a large venturi 11 and a small venturi 12 placed in such relation to each other in a well known manner as to exercise the proper influence responsive to the suction of engine 1, upon the discharge of a nozzle 13.

Nozzle 13 contains a compensating device 14, to the interior of which liquid fuel is supplied from float chamber 6 through a passage 15 and a restricted orifice 16. An annular space is provided by the nozzle 13 and compensator 14 to which leads a passage 17 open to atmosphere.

Nozzle 13 supplies liquid fuel and air to the mixing chamber 8, the air being passed interiorly of compensator 14 through a plurality of bleed orifices 18.

A casing 19 is adapted to slidably hold a valve 20, the stem of which at times closes the intake of passage 17 and has therein a small bleed passage 21. The upper part of casing 19 is connected to chamber 8 on the engine side of throttle 9 by passage 22, the lower part of casing 19 being connected to chamber 8 on the atmosphere side of throttle 9 by a passage 23. The upper part of casing 19 is closed by a plug 27, a spring 26 being placed therein between the head of valve 20 and plug 27.

Normally, when engine 1 is at rest, the action of spring 26 is to seat valve 20 firmly in passage 17 whereby access of air is cut off therefrom, except through the calibrated passage 21. If it be assumed that engine 1 is cold and the choker valve 10 is closed manually or otherwise for priming, and throttle 9 is substantially closed, upon cranking engine 1 to start the same, it will be seen that the same degree of vacuum will exist in chamber 8 on both sides of throttle 9, it being understood that there is a slight leak of air past both valves 9 and 10.

The cranking vacuum will thus be applied

to the same degree, when valve 10 is closed, through the passage 22 and 23 to each side of the head of valve 20, so that valve 20 will remain seated in passage 17, thereby throwing the full engine cranking suction on nozzle 13 to draw an excessive supply of liquid fuel therefrom for starting engine 1.

As soon as engine 1 fires, choker valve 10 will be opened whereby substantially atmospheric pressure will prevail in chamber 8 on the atmosphere side of throttle 9, when the same is closed. The idling vacuum on the engine side of valve 9 then will be high whereby valve 20 will be raised against the resistance of spring 26 to fully open passage 17.

It is to be understood of course that any well known idling feed and adjustment may be provided, but is not shown herein in order not to obscure the invention, whereby liquid fuel and air are provided on the engine side of throttle 9 when the same is closed, and during such idling periods it will be understood that no fuel or air are drawn from nozzle 13, except at low temperatures when valve 10 is partially closed.

Upon opening throttle 9 for increasing the speed of engine 1, the degree of vacuum above throttle 9 will decrease, and the degree of vacuum below throttle 9 will increase, whereby the difference in vacuum on each side of throttle 9 will be reflected by the movement of valve 20, in slightly closing passage 17. In this manner, at the proper speeds, and at varying degrees of opening of throttle 9, the suction applied to nozzle 13 will be broken by the supply of atmosphere through passage 17 and compensating orifices 18 to supply fuel and air to engine 1 in the proper ratio.

As a general rule, when throttle 9 is partially open so as to give an engine speed in an automobile of about 15 to 20 miles an hour, valve 20 will seat in passage 17 so that at higher engine speeds, a higher degree of suction and a richer fuel mixture will be provided from nozzle 13. This action gives the best economy at low speeds and gives the best power when it is required at high speeds.

In case that valve 10 is desired to be automatically operated according to the suction and/or temperature of engine 1, a casing 25 is provided forming a part of carburetor 4, wherein a valve 28 reciprocates according to the engine suction applied from above throttle 9 through a conduit 24. On one end of valve 28 is attached a flat spring 29 to which is fastened a pin 32 adapted to co-act with ratchet 30 comprising a short tooth 30a and a long tooth 30b, the same being fastened securely on spindle 31 supporting valve 10. The upper end of casing 25 is enclosed by a plug 35 supporting conduit 24 and a spring 36 serves to maintain valve 28 in predetermined positions.

On one side of casing 25 is placed a

cover 37 enclosing a thermostat 39, which supports a hollow valve 40, the walls of the latter containing ports 42 and 43 adapted to co-act at the proper time with a passage 41 leading from the interior of casing 25 to air passage 5 on the atmosphere side of valve 10 when the same is closed, and it will be noted that passage 41 is restricted to a small opening at its entry into casing 25, and at low temperatures, port 42 will be slightly open to passage 41.

A conduit 38 leads from the interior of cover 37 and may be wrapped around exhaust pipe 32 whereby the temperature of engine 1 may be reflected by the movement of thermostat 39.

The action of this device for automatically closing pipe 5 by means of valve 10 is as follows: Normally, valve 10, when engine 1 is dead, or at the proper operating temperature, is wide open being held in that position by a spring 34 attached to spindle 31 through an arm 33. Upon cranking engine 1 at low temperatures and throttle 9 being closed, engine vacuum will be applied through conduit 24 to the head of valve 28, whereby valve 28 will raise and thereby close valve 10 tight by pulling on the small tooth 30a.

Valve 10 will thus remain closed during cranking until sufficient fuel has been drawn through nozzle 13 to produce an explosive charge in the cylinders of engine 1, whereupon engine 1 will commence to idle, thus causing a sudden increase in vacuum applied through conduit 24, whereupon pin 32 will jump from the small tooth 30a and permit the recession of valve 10 a predetermined distance, depending on the distance of the tooth 30b from 30a.

Thereafter, upon opening throttle 9 for increasing the speed of engine 1, the vacuum applied to conduit 24 will decrease and thus permit the recession of valve 28 and valve 10 to the wide open position. The action of valve 28 may be modified by the action of thermostat 39 and valve 40 because as soon as engine 1 fires, the velocity of air in passage 5 past the mouth of passage 41 will increase and thus depending on the position of valve 40 responsive to thermostat 39, a greater or less suction will be applied through passage 41 to the lower side of valve 28, for either expediting or delaying its movement.

For instance in very cold weather, port 42 will be not quite closed, while port 43 is always open to passage 41 under every condition, therefore the effect of suction on valve 28 at very low temperatures is negligible and a dashpot action in casing 25 is provided, depending on the size of the restriction in passage 41. With increasing engine temperatures, thermostat 39 will expand due to the heated air being drawn through conduit 38, valve 40, port 42, and passage 41 responsive to the engine suction and ultimately port 42

will be in full registry with passage 41 at optimum engine operating temperatures to the end that the full suction applied to passage 41 will tend to quickly open valve 10 in proportion as throttle 9 is quickly opened.

In this manner, the temperature of engine 1 will control the action of valve 28 for modifying the effect of engine suction applied to nozzle 13 and thus modifying the richness of the mixture applied therethrough.

Referring to Figs. 5 to 7 inclusive, an arrangement is shown wherein casing 19 contains a plurality of valves 45 and 49, the stem of valve 49 being concentric with the stem of valve 45, and valve 45 now controls an extension of passage 17 wherein an excess of liquid fuel is supplied from chamber 6 and passage 15 through a restricted orifice 44. On the lower side of the head of valve 45 atmosphere is admitted to the interior of casing 19 through a port 47 and thence at the proper time, through a port 48 to the interior of valve 45. A port 46 is adapted to register at the proper time with the passage 17, when the lower part of valve 45 is seated in the extension thereof for cutting off the supply of liquid fuel through orifice 44.

A spring 50 is placed between the heads of valves 45 and 49 and a spring 52 is placed between the head of valve 49 and the cover 27, and said springs are of the proper relative strengths. The stem of valve 49 is hollow and contains a port 51 adapted to co-act at the proper times with port 48 for permitting the regulated passage of air through ports 47 and 46 to the compensating orifices 18. Passage 23 is now connected to the casing 19 between the head of valves 45 and 49 and to the chamber 8 in an enlarged portion thereof, it being particularly noted in both the devices illustrated that air passage 5 is much larger in cross sectional area than the mixing chamber 8 which is further restricted by the venturis 11 and 12, in order to properly control the air stream passing through the venturis.

The automatic closing of valve 10 is effected in like manner as already described, except that the temperature control of valve 28 may be governed by the expansion of air in bulb 55 placed on exhaust pipe 2 and led therefrom through a capillary tube 54, or tube of small bore, to an extension 53 of cover 35 wherein a piston 56 is reciprocated by valve 28 through a hook connection 57, piston 56 being very closely machined to prevent escape of atmosphere there past. It is of course obvious that a diaphragm or bellows may enclose the end of extension 53 for a like object.

Referring to the action of valves 45 and 49, if it be assumed that throttle 9 is closed for starting and valve 10 is closed either automatically or manually, the cranking vacuum for starting will be applied equally on each side of the head of the piston 49 through pas-

sage 22 and 23, and therefore piston 49 will not move. The same vacuum however is applied to the head of the valve 45 thus causing the same to rise and permit the passage of excess fuel for priming through orifice 44 and 70 passage 17, port 46 being shrouded to prevent the passage of atmosphere. In this manner the normal richness of supply through orifice 16 will be augmented by the supply through orifice 44 for giving a rich 75 priming mixture to start the engine. As soon as engine 1 is idling, valve 10 will be more or less open, thus decreasing the vacuum below throttle 9 and causing valve 5 to seat. The idling vacuum above throttle 9 will be a 80 maximum thus causing valve 49 to rise, and causing port 51 to register with port 48, whereby atmosphere will pass through ports 46, 47, 48, and 51 to the compensating orifices 18 for reducing the richness of the mixture 85 supplied through nozzle 13.

Thereafter as throttle 9 is opened, the registry of port 51 with port 48 will decrease to the end that at wide open positions of throttle 9, a minimum amount of air will be supplied 90 to orifices 18.

It will be understood that valves 45 and 49 may be suitably guided with respect to casing 19, passage 17 and to each other to the end that the various ports will always register at 95 the proper position of throttle 9 for giving a proper effect on nozzle 13.

Also, a plurality of orifices 51 may be provided to get the best effect under every condition of engine operation for providing air 100 bleed to the compensating orifices 18.

Valves 45 and 49 form a compensating device in a straight line for controlling the richness of the mixture under all conditions and act to give economy in operation according 105 to the requirements of engine 1 reflected by the degree of vacuum in chamber 8. Also great simplicity of construction is possible.

The entry position of passage 23 into chamber 8 may be determined for any particular design and may at times be connected to the throat of either venturi 11 or 12 depending on the movement required of valve 45. For instance, if passage 23 be connected to the throat of venturi 12 and orifice 16 is restricted for low speed supply, the higher speed vacuum may be applied to valve 45 for slightly raising the same for high speed fuel supply.

It will be noted that, while the automatic operation of valves 10, 45 and 49 are interdependent for controlling the full range of engine operation from starting at low temperatures to running at optimum temperatures, at the same time the automatic operation of valves 45 and 49 are fully effective if 125 valve 10 is manually operated and thus the priming and economizer actions are readily available.

The cut of teeth 30a and 30b are such as to give the described action, i. e. first closing 130

valve 10 tight at cranking vacuum and thereafter, on an increase in vacuum, permitting valve 10 to open a predetermined amount. The movement of valve 28 and the tension of spring 36 will also be designed to this end.

I claim as my invention:

1. A carburetor having a mixing chamber, a nozzle discharging into the chamber, a liquid fuel supply for the nozzle, a throttle 10 governing the outlet from the mixing chamber, a casing having a pair of openings connected to the mixing chamber, one on each side of the throttle and means in the casing responsive to the differential suction on said openings for controlling the discharge of liquid fuel from the nozzle.
2. A carburetor having a mixing chamber, a nozzle discharging into the chamber, a liquid fuel supply for the nozzle, a main 20 air supply for said mixing chamber, a secondary air supply for the nozzle, a throttle governing the outlet of fuel and air from the mixing chamber, a casing connected to the mixing chamber on each side of the throttle and means for effecting said secondary air supply in the casing responsive to the throttle position for controlling the discharge of liquid fuel and air from the nozzle.
3. A carburetor for an internal combustion engine to which it is attached, comprising 30 a mixing chamber, a main air passage leading to the mixing chamber, a fuel nozzle discharging into the mixing chamber, a liquid fuel supply for the nozzle, a posterior throttle in the mixing chamber, an anterior throttle in the air passage and means connected to the mixing chamber on each side of the posterior throttle operative upon movement of the anterior throttle, for controlling the discharge of liquid fuel from the nozzle.
4. A carburetor for an internal combustion engine to which it is attached, comprising 45 a mixing chamber, a main air passage leading to the mixing chamber, a fuel nozzle discharging into the mixing chamber, a liquid fuel supply for the nozzle, a posterior throttle in the mixing chamber, an anterior throttle in the air passage and suction means connected to the mixing chamber on each side of the posterior throttle operative upon movement of the anterior throttle for controlling the discharge of liquid fuel from the nozzle.
5. The combination with an internal combustion engine of a liquid fuel supply, a carburetor having a nozzle connected with the liquid fuel supply, a main air supply and a 50 throttle therefor, a discharge throttle for the carburetor, a casing connected to the carburetor on each side of the discharge throttle, a secondary air supply leading to the nozzle and means operated by engine suction for effecting the secondary air supply for controlling the discharge of fuel from the nozzle.

6. The combination with an internal combustion engine of a liquid fuel supply, a carburetor having a nozzle connected with the liquid fuel supply, a main air supply and a throttle therefor, a discharge throttle for the carburetor, a casing connected to the carburetor on each side of the discharge throttle, a secondary air supply leading to the nozzle and means operated by engine suction for controlling the secondary air supply for 70 controlling the discharge of fuel and air from the nozzle.

7. The combination with an internal combustion engine of a liquid fuel supply, a carburetor having a nozzle connected with the liquid fuel supply, a main air supply and a throttle therefor, a discharge throttle for the carburetor, a secondary air supply and a control valve therefor for controlling the discharge of fuel from the nozzle and means operated by engine suction for controlling said valve upon movement of the main air supply throttle, said means including a conduit extending to a point posterior of the 75 throttle.

8. The combination with an internal combustion engine of a liquid fuel supply, a carburetor having a nozzle connected with the liquid fuel supply, a main air supply and a throttle therefor, a discharge throttle for the carburetor, a valve for controlling the discharge of fuel from the nozzle and means operated by engine suction and temperature for controlling said valve upon movement of the main air supply throttle.

9. A carburetor having a mixing chamber, a throttle in the mixing chamber controlling the discharge therefrom, a nozzle discharging into the mixing chamber, means to supply liquid fuel to the nozzle, means to introduce air into the nozzle, means to apply suction to the mixing chamber, and suction operated means on the nozzle side of said throttle for controlling the discharge of liquid fuel and air from said nozzle.

10. A carburetor operable by the suction of an internal combustion engine comprising a mixing chamber, a liquid fuel supply, a throttle in the mixing chamber, a nozzle connected with the fuel supply and discharging into the mixing chamber, and suction operated means connected with the mixing chamber on each side of said throttle for regulating the discharge from said nozzle.

11. The combination with a carburetor operable by suction and having a main air passage and a throttle therefor, a mixing chamber and a throttle therefor, a liquid fuel supply, a nozzle connected with the fuel supply and discharging into the mixing chamber, suction operated means controlling the discharge from the nozzle of means operated by suction independently of first named means for controlling the main air passage throttle.

12. In a fuel feeding system for internal 130

combustion engines, a mixing chamber, a nozzle discharging in said chamber, a throttle posterior of said nozzle, a main air passage, a choker valve in said passage, an auxiliary air 5 passage for delivering air to said nozzle, a valve for controlling said passage, and suction operated means for independently controlling said valves.

13. The combination with an internal combustion engine of a liquid fuel supply, a carburetor having a nozzle connected with the said fuel supply, a main air supply and a throttle therefor, a discharge throttle for the carburetor, a valve operably connected 15 to the carburetor at opposite sides of said discharge throttle, and a secondary air supply leading to said nozzle and controlled by said valve, said valve being operated by engine suction whereby to control the discharge of 20 fuel and air from said nozzle.

14. The combination with an internal combustion engine of a liquid fuel supply, a carburetor having a nozzle connected with said fuel supply, a main and a secondary air supply, a throttle for said main supply, a discharge throttle for said carburetor, said secondary air supply communicating with said nozzle, and a valve having connections at opposite sides of said discharge throttle and 30 controlled by engine suction through said connections, said valve being operated upon movement of the main air supply throttle.

In testimony whereof I affix my signature.
CHARLES LAWRENCE STOKES.
